CLAIM

The ornamental design for a sport shoe as shown and described.

DESCRIPTION

FIG. 1 is a perspective view of a sport shoe showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The lines used inside the toe and heel features represent stippling. The broken lines illustrate portions of the sport shoe that form no part of the claimed design.
